UNITED STATES PATENT OFFICE.

CHARLES H. COLVIN, OF CHATTANOOGA, TENNESSEE, ASSIGNOR TO ELIZABETH ELLIS COLVIN.

FLUSHING MECHANISM FOR WATER-CLOSETS.

1,218,610.

Specification of Letters Patent.

Patented Mar. 6, 1917.

Application filed May 2, 1916. Serial No. 94,995.

To all whom it may concern:

Be it known that I, CHARLES H. COLVIN, a citizen of the United States of America, residing at Chattanooga, in the county of 5 Hamilton and State of Tennessee, have invented certain new and useful Improvements in Flushing Mechanisms for Water-Closets, of which the following is a specification.

This invention relates to flushing apparatus in which a seat controlled valve mechanism is employed in connection with an air tight water reservoir to automatically flush water closet bowls and the like.

One object of my invention is to adapt the 15 several parts of the valve mechanism which are subject to wear and require replacement to be removed bodily from the piping system without disconnecting the latter or making it necessary to shut off the water supply.

20 The latter feature of my invention is obtained by the provision of an auxiliary throttling valve in the water supply pipe below the seat controlled valves, which throttling valve will be automatically seated.

25 when the seat controlled valve mechanism is in flushing position or is withdrawn, and will permit a negligible flow of water past its seat for the purposes hereinafter explained. In making the seat controlled 30 valve mechanism readily removable, the several valves are mounted in alinement on a stem which is preferably sectional and which is endwise removable upwardly from the piping system.

35 Another feature of my invention resides in the means for governing the opening movement of the valve controlling the flow of flushing water from the reservoir to the bowl, my object being to make the flow of

40 water to the bowl substantially uniform during the opening movements of the valve so that any tendency to splash out of or over the bowl is avoided. To this end I adapt the flushing valve to open only partially responsive to the seat control and to complete its opening movement responsive to the action of the gradually accumulating water pressure, which leaks past the auxiliary throttling valve, against a piston which assumes 45 a pressure tight fit in the piping system when the valve has partially opened.

Another feature of my invention consists in providing means for graduating the flow of water as it enters from the supply pipe 55 so that the operation of the valves of the

mechanism is noiseless, thereby insuring a gentle closing without hammer or jamming.

My invention further comprises the novel features of construction and arrangements of parts which are hereinafter more particularly described and claimed, and which in their preferred embodiment only are illustrated in the accompanying drawings, in which:—

Figure 1 is a side elevation of the complete 65 flushing mechanism.

Fig. 2 is a vertical longitudinal section through one form of water closet flushing mechanism constructed according to my invention.

Fig. 3 is a partial view similar to Fig. 2 showing the auxiliary valve in closed position.

Fig. 4 is a cross sectional view on the line 4—4 of Fig. 2.

Fig. 5 is a side elevation of the auxiliary valve stem; and

Fig. 6 is a sectional view on the line 6—6 of Fig. 5.

Similar reference numerals refer to similar parts throughout the drawings.

In describing the preferred embodiment of my invention, the flushing apparatus comprises a vertical pipe consisting of sections 1, 2, 3 and 4, respectively.

The top section 1 is provided with two substantially horizontal outlets 5 and 6 disposed in opposite directions but at different levels. The former 5 connects with a water closet bowl 7, whereas the latter 6 connects 90 with an air-tight reservoir 8, partially shown in Fig. 1.

At the lowest point of the bottom section 4 of the vertical pipe a water supply pipe 9 is tapped in, said water supply pipe leading 95 from a service main not shown. Immediately above the upper end of the section 4 and leading out from section 3 is a drain outlet 10. On the inside of section 4 is located a valve seat 11 provided with an aperture 12 through which an auxiliary valve stem 13 extends. Said valve stem is threaded at its lower end 13^a which carries a nut 14 and serves as the auxiliary valve. Neither the auxiliary valve, nut 14 nor its seat 11 105 are ground to make a tight joint, as it is intended that there shall be a slight flow of water past this valve when seated as indicated by arrows, Fig. 3, for the purposes hereinafter explained. The upper end of 110

said valve stem is provided with a head 15 shaped as shown in Fig. 6, that is to say, provided with four corners 16 which center it and prevent the head from entering the section 3 of pipe next above, and yet permit the incoming water to pass by the same.

The stem is provided above the auxiliary valve 13^a with grooves 17 as best shown in Fig. 5 which, as the stem reciprocates, gradually 10 ate the flow of water permitting first a minimum flow gradually increasing to maximum, and in closing gradually cutting off the flow until the flow is reduced to the leakage past valve 13^a. Confined between the head of the 15 stem and the seat 11 is a spring 18 which tends to seat the auxiliary valve and to maintain the same in a seated position so that it will substantially cut off the supply of the 20 service main and permit repairs to the apparatus above it in the piping system.

In the top section 1 above and in line with the bore of the sections 2, 3 and 4, is a top opening which is normally closed by a cap 18^a held in place by any easily detachable 25 means and provided with a stuffing box 19 through which the valve stem 20 extends. The first section of the valve stem is threaded as shown at 21 and carries the disk 22 against which the valve 23 bears. The valve 30 30 comes to a seat on the shoulder 24, thus cutting off the flow from reservoir 8 to the bowl 7. The valve stem 20 continues downwardly as shown at 25 and the head of section 25 connects with another section 26 which also connects with a third section 27, suitable socket joints, such as 28, forming the connection and being fixed by pins 29. The bottom section 27 carries the member 30 which works in pipe section 3 and has 35 holes 31 which permit the water to pass. Said member 30 is provided with a peripheral groove which accommodates a split packing ring 32 that will expand and form a tight joint with the bore of pipe section 3. 40 The end of section 27 of the valve stem 20 is provided with the disk 34 and the threaded tip 35. A cup 36 rests against disk 34 and is retained in place by a nut 37, thus forming a piston valve which works within 45 the lower end of pipe section 3 and within the upper end of pipe section 4, which is enlarged to provide a chamber 38 sufficiently large to permit the water to by-pass the piston when the latter is in the position shown 55 in Fig. 2.

The upper section 1 of the vertical pipe is provided with a bracket 39 which has pivotally fulcrumed thereon at 40 a lever 41, the forward end of which carries the seat 60 portion 42, whereas the rear end carries the counter-balancing weight 43. The upper end of the valve stem 20 is provided with a threaded length 44 onto which is screwed a cap 45 secured in place by a suitable set 65 screw 46. It will be noted that the head 15

at the top of the auxiliary valve stem 13 forms the upper seat for the spring 18 and is adapted to be engaged and depressed by the valve stem section 35 when the latter is in its lowered position, as shown in full lines Fig. 70

2. The main valve stem however is not connected to the auxiliary valve stem and thus the spring 18, which urges the latter upwardly, can exert an influence through the sectional stem to open valve 24 only partially or to its dotted line position, Fig. 2, 75 as the seat 11 will engage the nut 14 and limit the stroke of the spring. When the valve 23 is in approximately half open position the piston 36 will have moved out of the 80 chamber 38 and assumed substantially fluid tight position in the lower end of the pipe section 3.

In operation, assuming the reservoir 8 emptied by the previous flushing and the 85 seat elevated, as shown in Fig. 1, upon the depression of the seat it will engage the valve stem and move it downwardly, with the following results. The valve 23 will seat tight against its seat 24 and shut off communication between the bowl and the piping system; the piston valve 36 will be forced out of its seat in the lower end of the pipe section 3 and into the chamber 38; and stem 35 in thus moving will engage the stem 13 and 95 open the auxiliary valve 13^a. As a result the water from the supply mains will pass up, flowing with increasing volume as stem 13 is lowered, through the piping system into the reservoir, which was left empty after the 100 previous flushing operation. Upon release of the seat 42 its counterbalance weight will raise it and relieve the valve stem 20 of pressure, whereupon the following operations take effect in the valve mechanism, 105 namely; the valve 23 will open responsive to the water pressure below it in the piping system and to the thrust of the spring 18, but this initial opening movement is only partial, due to the fact that the engagement of 110 the valve 14 with its seat 11 brings about a definite limit to the action of the spring, which limit takes place approximately contemporaneously with the entrance of the piston valve 36 with fluid tight fit into its 115 cylindrical seat at the lower end of the pipe section 3 and with the arrival of the valve 23 at its half open or dotted line position, Fig. 2. It will be at once apparent that when the piston valve 36 enters the pipe 3, 120 the valve 23 becomes substantially balanced and will stand in this position until the gradual leakage of water past the auxiliary valve 13^a and through the grooves 17 in its stem 13 will establish the water main pressure in the chamber 38 below the piston 36, 125 thus unbalancing the valve parts and forcing the plunger upwardly to raise valve 23 gradually to its full open position. By this means the initial opening of the bowl supply 130

valve is small, avoiding the heavy rush of water and the heavy splashing and after the high pressure in the tank has been largely reduced the valve will automatically open fully and permit the tank to discharge itself, the resultant action of the valve 23 being such that what may be termed a fairly uniform volume of water is delivered to the bowl.

10 It will be observed that the piston valve 36, when in its dotted line position Fig. 2, will positively shut off the flow of water, and when in this position the valve 32 will have moved above and cleared drain port 10 so that the piping system above valve 36 will be drained. It will be obvious that the arrangement of the pipes and valve stems in section is for convenience in assembling and that such an arrangement may be departed 15 from within the scope of my invention.

10 The valve end 13^a of this auxiliary valve stem 13 does not make a water tight fit in the opening in seat 11 but, like valve 14, permits a restricted flow of water which is calculated to raise the water pressure in chamber 38 sufficiently to start the final movement of the piston valve 36 and govern the complete opening movement of the flushing valve 23 within a predetermined time interval.

30 The particular downwardly tapering shape of the grooves 17 in the auxiliary valve stem, as shown in Fig. 5, is essential in producing the graduated increase or decrease of the water flow which will make 35 noiseless the operation of the valve. The grooves 17 not only taper downwardly in width but also increase in shallowness toward their lower end which features co-act to cause the grooves to effect a graduated increase or decrease of the water flow to accomplish the ends above stated.

Having thus described my invention, what I claim as new and desire to secure by Letters Patent, is:—

45 1. A flushing mechanism comprising in combination, a bowl, a movable seat therefor, a reservoir, a water supply pipe, a valving means comprising a valve controlling the flow of water from the supply pipe to the 50 reservoir, and a flushing valve controlling the flow of water from said reservoir to said bowl, seat controlled means adapted to partly open the flushing valve which is adapted to be completely opened by the water 55 supply pressure, and automatic means acting on the water supply valve to retard the final opening movement of said flushing valve.

60 2. In a flushing mechanism, a bowl, a movable seat, a reservoir, a water supply pipe having upper and lower valving chambers, a valve stem having thereon a flushing valve in the upper chamber controlling the flow of water from said reservoir to said bowl 65 and a piston valve in said lower chamber

controlling the flow of water to said reservoir, there being an opening in said pipe through which said stem with both valves can be bodily withdrawn and reinserted, spring means controlled by the seat to partly open the flushing valve and close the piston valve which is adapted to be moved by water pressure to fully open the flushing valve, and means controlled by said stem to retard the accumulation of water pressure to move the piston.

70 3. In a flushing mechanism, in combination with a bowl and reservoir, a water supply pipe, a valve stem having a supply valve controlling the flow of water to said reservoir from said supply pipe, and a flushing valve controlling the flow of water from said reservoir to said bowl, and means unattached to but controlled by said valve stem for graduating the flow of water through 80 said supply pipe to said supply valve as the valve stem is actuated to insure noiseless operation.

75 4. In a flushing mechanism, in combination with a bowl and reservoir, a water supply pipe having connections to both bowl and reservoir, a valve stem having a supply valve controlling the flow of water from the supply pipe to said reservoir, and a flushing valve controlling the flow of water from 90 said reservoir to said bowl, a throttling means in said supply pipe in advance of said supply valve and comprising a seat and a valve, adapted to assume a throttling position in said seat responsive to the water 95 pressure and having grooves which taper acutely in the direction of its opening movement relatively to said seat and which are adapted to graduate the flow through said supply pipe to said valves for the purposes 100 described, said grooved valve being controlled in its movements by said first mentioned valve stem.

5. In a flushing mechanism, in combination with a bowl and a reservoir, a water 110 supply pipe having connections to the bowl and reservoir, a valve stem having a flushing valve controlling the flow of water from said reservoir to said bowl and a piston valve to cut off the flow of water from said supply pipe to said reservoir at an intermediate point in its closing travel, and means to control the action on said piston valve of the water supply pressure which is adapted to complete its closing movement and to 115 govern the full opening movement of the flushing valve, as and for the purposes described.

6. In a flushing mechanism, the combination with a bowl and a reservoir, of a water supply pipe, a valve stem carrying a downwardly closing flushing valve for controlling the flow of water from said reservoir to said bowl, and an upwardly closing piston valve to cut off the flow of water from 120 125 130

41
said supply pipe to said reservoir, said piston valve having an elongated seat with which it is adapted to assume closed relation when the flushing valve is partway 5 open, said piston valve being adapted to be moved to the end of its closing travel by the water supply pressure, and automatic means to control the accumulation of said water supply pressure below the piston valve to 10 govern its movements and the opening of the flushing valve, substantially as and for the purposes described.

7. In a flushing mechanism, the combination with a bowl, a reservoir and a water 15 supply pipe, of a valve stem having a flushing valve for controlling the flow of water from the reservoir to the bowl, a piston valve for controlling the flow of water from the supply pipe to the reservoir, spring 20 means adapted to act on said valve stem when the supply valve is seated to positively start the opening movement of said flushing valve, means to limit the action of the spring to relieve the flushing valve of its influence 25 when the latter is partway open, and means to utilize the water supply pressure to complete and control the further opening movement of the flushing valve.

8. In a flushing mechanism, the combination 30 with a bowl, a reservoir and a water supply pipe, of a valve stem having a flushing valve which seats against the water pressure and controls the flow of water from said reservoir to said bowl, and a piston 35 valve which seats with the water pressure and controls the flow of water from said supply pipe to said reservoir, said piston valve having an elongated seat against which it closes when the flushing valve is partway 40 open, a spring adapted to act on said valve stem to close the piston valve, a stop for the spring which limits its action on the stem to a point where the piston valve is closed and the flushing valve is part open, and an 45 auxiliary valve means adapted to be opened by said valve stem and to seat automatically, said auxiliary valve, when seated, permitting a restricted flow of water past it to act on the piston valve to move it to complete the opening movement of said flushing 50 valve, substantially as described.

9. In a flushing mechanism, a bowl, a reservoir, a water supply pipe, connections from one end thereof to the water mains and 55 from the other end of said reservoir and bowl, a valve stem in said supply pipe endwise removable therefrom, a flushing valve and a piston valve on said stem, said valves being removable with the stem bodily from 60 said supply pipe without disconnecting the

latter, seats for said valves, the piston valve seat being closed by the piston valve near the middle of its closing travel, an auxiliary valve, a seat therefor in advance of the piston valve seat, a spring tending to move 65 said auxiliary valve toward the piston valve to seat it, and said auxiliary valve engaging its seat when the valve stem has been moved by its spring to partway open the flushing valve and to close the piston valve, said auxiliary valve having means to permit a graduated flow of water past it as it opens and being adapted to permit a restricted flow of water past it and into the supply pipe when seated.

7. In combination with a reservoir, a bowl, and a depressible seat for the bowl, of mechanism for controlling the flushing of said bowl comprising a water supply pipe, a valve stem in said pipe and projecting therefrom in position to be depressed by said seat, a flushing valve on the upper end of said stem adapted to be seated when the stem is depressed to shut off communication between the reservoir and bowl, a piston valve on the lower end of said stem for controlling the supply of water to said reservoir, said piston valve having a seat which it engages at an intermediate point of its closing movement and when the flushing 90 valve is partway open, spring means to partway open the flushing valve with a positive movement, and self closing valving means operable by but disconnected from said valve stem for regulating the access of the 95 supply water pressure to the piston valve to govern by the action of such water pressure on said piston valve the completion of the opening movement of the flushing valve.

11. In a flushing mechanism, the combination 100 with a bowl, a reservoir, a supply pipe including connections to both bowl and reservoir, a valve stem having a flushing valve controlling the flow of water from the reservoir to the bowl, a piston valve 105 controlling the flow of water from the supply pipe to the reservoir, and an auxiliary valving means normally seated and disposed to be unseated by said stem when the flushing valve is seated, said auxiliary valve being adapted to permit a graduated leakage 110 of water past it into the supply pipe below the piston valve, and tapering by-passes on said auxiliary valve to gradually restrict or enlarge the flow of water past it noiselessly as the first mentioned valves are operated, substantially as described.

In testimony whereof I affix my signature.

CHARLES H. COLVIN.
